[57] **CLAIM**

The ornamental design for a multi-level gym, as shown and described.

DESCRIPTION

FIG. 1 is a top plan view of a multi-level gym showing my new design;

FIG. 2 is a front elevational view thereof with portions thereof shown in fragment;

FIG. 3 is a rear elevational view thereof;

FIG. 4 is a right end elevational view thereof;

FIG. 5 is a left end elevational view thereof; and

FIG. 6 is a front end perspective view thereof shown on a slightly enlarged scale; and,

The unshown bottom of the design is substantially flat plain and unornamented.

FIG. 1

FIG. 2

FIG. 3
